UNITED STATES PATENT OFFICE.

REYNOLD J. RICE, OF WATERLOO, IOWA.

HANGER FOR EARS OF CORN.

1,211,234.

Specification of Letters Patent. Patented Jan. 2, 1917.

Application filed August 21, 1913. Serial No. 785,927.

To all whom it may concern:

Be it known that I, REYNOLD J. RICE, a citizen of the United States of America, and a resident of Waterloo, Blackhawk county, 5 Iowa, have invented certain new and useful Improvements in Hangers for Ears of Corn, of which the following is a specification.

My invention relates to improvements in hangers for ears of corn, and the object of 10 my improvement is to furnish a hanging device formed of detachably connected inter-linked parts, each part having securing means for ears of corn suitable to hold the ears apart in proper positions for drying 15 and preservation. This object I have accomplished by the means which are herein-after described and claimed, and which are illustrated in the accompanying drawings, in which:

20 Figure 1 is an elevation of a plurality of the interlinked hanger parts as suspended, and as holding a number of ears of corn, on a reduced scale. Fig. 2 is a side elevation of 25 one of the detachable hanger parts, full size. Fig. 3 is an upper plan view of one of the said hanger parts, full size.

Similar numerals of reference denote corresponding parts throughout the several views.

30 It has been my purpose to supply a hanging-means for ears of seed corn, which will be not only simple and inexpensive, but also having its parts capable of quick detachment for convenient storage or transportation. With this end in view, I have formed 35 each hanger part 1 of a single piece of rather stiff wire, bent into the form shown, described as follows: Each hanger part is first bent medially to form a semi-circular 40 medial curve or loop 5, each of the members extending parallel in one direction from said loop, being then bent at a short distance from the loop to produce down-turned portions 4 convergingly, and then bent again 45 outwardly to produce angles 6 with short oblique downwardly and outwardly directed parts 3 in the same plane as the parts 4, said members being then again bent at the angles 7 to produce oblique upwardly and outwardly directed extremities 2, also lying in 50 the same plane.

A plurality of said devices may be readily connected together by slipping the looped part 5 of one device between the parts 4 of 55 another device, and drawing the first up

until the loop 5 on the second device embraces and is secured about the angles 6 of the latter device. In this position, the lowermost device is securely suspended from the uppermost device, the outwardly sloping parts 3 of the upper device preventing the loop 5 of the lower device from slipping, and holding it securely in place. As many of these devices may be thus connected detachably together as may be desired, and the 60 loop 5 of the uppermost device may be then hung on a nail or other object 9.

The parts 2 may be sharpened, as shown in Fig. 1, at their extreme points, although that is not absolutely essential, since it is 70 easy to push the ends of the parts 2 into the basal portions of the cobs of the ears 8, the ears then being supported on said parts in an obliquely upward direction, as indicated in said Fig. 1.

The piercing of the cobs tends to aerate them, and assist in the drying process, while the supporting of the ears, separated as shown, keeps them distinct from each other, and easy of identification when preserved 80 for seed.

75 The seed devices 1 may be disassembled by drawing down the loop 5 on the uppermost device, turning the device to one side, and withdrawing it between the parts 4 of the lower device. Since these devices are small 85 and lie mostly within the same plane, many of them may be packed in a receptacle for storage, or transportation, using comparatively little storage space. Since the looped parts 5 transmit the weight of the suspended load to the inclined parts 3 of the device above, said parts 3 are, by reason of their obliquity, drawn together elastically, and thus securely held from spreading.

90 Having described my invention, what I claim as new, and desire to secure by Letters Patent, is:

1. A seed-corn hanger, consisting of a plurality of like bodies detachably linked together, each body being an elastic rod doubled over to form a medial loop extending angularly to one side of spaced members, the members being oppositely bent to form their extremities into upwardly directed prongs, 100 and the loop of each rod being linked about the members of the rod immediately above at the location of outward bending of said prongs.

105 2. A device of the character described, 110

comprising a plurality of interlocked units, each of said units being formed from a single piece of wire bent upon itself to form spaced elongated strands capable of relative movement, the free extremities of which are directed laterally and upwardly to afford impaling prongs, the opposite end portions of the strands being flexed angularly to afford an engaging means adapted to coact 10 with the impaling prongs of an adjacent

unit, said impaling prongs being positioned in substantially the same longitudinal plane occupied by the spaced strands.

Signed at Waterloo, Iowa this 2nd day of Aug. 1913.

REYNOLD J. RICE.
